COUNTERBALANCE

Carl W. Clements, Aurora, Ill.

Application June 20, 1940, Serial No. 341,567

4 Claims. (Cl. 105—37)

This invention relates to improvements in locomotive and similar engines and more especially to the mechanism with which a driven shaft is rotated. In the instance of the locomotive which is herein exclusively used as the example of engine to which the invention is applied, the rotary or driven shaft is regarded as the main axle.

It is commonly known among persons skilled in this particular art that the main axle must be counterbalanced in order to approach a rhythmic rotation, in other words, a character of rotation of substantial uniformity that will insure a vibrationless operation. The latter achievement, however, falls short of realization in actual practice, because despite the counterbalancing of the crank pins there yet remains an unbalanced component which makes itself evident in an unwanted vibration in the axle despite all known efforts to damp it out. Accordingly the instant invention comprises the development of a mechanism for the overcoming of the known defects, the objects being briefly stated as follows:

First, to provide a mechanism for so counterbalancing the main axle of a locomotive or equivalent mechanism, that known unbalanced components are eliminated.

Second, to provide a counterbalance for a locomotive or equivalent engine wherein reciprocating parts are employed in producing rotary motion.

Third, to provide a counterbalance which practically eliminates the unbalanced components found in the conventional counterbalancing systems used in converting reciprocating motion into rotary motion, the improvement herein employed utilizing a system of weights counterrotative to the actual motion of the machine.

Other objects and advantages will appear in the following specification, reference being made to the accompanying drawings, in which:

Figure 1 is a view in perspective of a counterbalance constructed according to the principles of my invention.

Figure 2 is an end elevation of one end of the main axle and parts carried thereby.

Figure 3 is a detail cross section taken on the line 3—3 of Fig. 2.

Figure 4 is a cross section taken on the line 4—4 of Fig. 1.

Figure 5 is a cross section taken on the line 5—5 of Fig. 1.

Figure 6 is a horizontal section of the counterbalancing mechanism, parts being shown in elevation.

Figure 7 is a vertical cross section taken on the line 7—7 of Fig. 6.

Figure 8 is a detail view of the floating yoke.

Figure 9 is a cross section taken on the line 9—9 of Fig. 1.

Figure 10 is a bottom view in perspective of my counterbalance shown applied to the wheels and axle of a locomotive.

In carrying out the invention use is made of the main axle 1 as the foundation for the counterbalance generally designated 2, the function of which is to damp out, so to speak, hitherto inaccessible unbalanced components which have become perceptible in the driving of said axle. 15 The latter carries main driving wheels 3, 4, at its ends. These are affixed to the axle by pins 5 or any known equivalent, and although comparatively small in the drawings they are intended to represent the main driving wheels of the locomotive.

It is to be borne in mind that since Figs. 1 and 10 are substantially identical, the same reference numerals are employed in both figures.

These wheels and the wheels which they represent, together with the main axle 1, obviously are elements of common knowledge. This is also true of the pitmans 6, 7, the piston rods 8, 9 and the cylinders 10 in which pistons such as 11 are reciprocated by the introduction of steam. The 30 valve mechanism by which the functions of lead and cut-off are accomplished is omitted. In each instance a wrist pin 12 pivotally joins the respective pitman to a cross head 13 which is a more or less integral part of the piston rod.

35 Further describing the known structure, the respective pitmans 6, 7, are connected to crank pins 14, 15 of the wheels 3, 4. At points diametrically opposite to the positions of the crank pins and centered on the wheels at identical radial

40 distances are sets of counterweights 16, 17. The weights are of any known character, and they are supplemented by subordinate cross counterbalance weights 18, 19, the function of which is to complete the counter-balancing of the main

45 axle according to known methods. It is to be observed that the crank pins 14, 15, are set 90° apart. This angular spacing also extends to the counterweights and their subordinates and necessarily so for the arrival at as near a balanced

50 condition of the main axle as possible.

From here on the description relates to the counterbalance 2 and all the parts which it comprises. The axle 1 is supported by main bearings 20 which are firmly secured at 21 to a platform 22. This platform is to be regarded broadly

as part of the engine frame and it is suspended in a fixed position by studs 23 which extend up to some point of fixed securement.

Each of the main bearings 20 unlike known bearings of the same kind, is slotted at 24. The axle 1 is thus admitted readily, and when it is emplaced in its bearings, it rests upon the bottoms of the slots which bottoms are considerably lengthened by the addition of bosses 25. The axle 1 revolves upon these bosses, but it has a permissible up and down motion due to the vertical relationship of the slots 24. The collars 26, 27 on the axle 1 and located on opposite sides of the bosses 25 are held in bearing relationship to the latter by pins 28 that are driven through the axle. The latter is thus prevented from end-wise movement although the up and down movement can occur when required.

A double-faced bevel gear 29 is secured at 30 to the axle 1 centrally of its length. The gear faces are designated 31 and 32. These faces are confronted by the gears 33, 34, of what are herein known as gear and disk counterweight couples 35, 36. Said couples and the double-faced gear together with their connecting pinions constitute a sole counterbalancing unit which is centered upon the axial distance of the axle 1. The disks of these couples are denoted 37 and 38. They are intended in practice to be of the same size as the wheels 3, 4, which means that in the event of the latter comprising the locomotive drivers the disks 37, 38, would be equally as large as to spacing of counterbalance weights, i. e., the same distance from the center of the driving axle as the crank pins 14, 15.

The couples 35, 36, are completed by sleeves 39, 40, which connect the respective gears and disks 33, 34, and 31, 38. These sleeves are loosely mounted on the main axle 1 for the purpose of responding to an effort to rotate them counter to the direction of rotation of said main axle. To illustrate this point the main axle and its affixed wheels are rotated in the direction of arrows a (Fig. 1) by the operation of the engine cylinders. The gear 29 being affixed to the axle rotates in the same direction (arrow b, Fig. 1). But the couples 35, 36 are rotated reversely in the direction of the arrows c (Fig. 1).

This effect is accomplished by a pair of pinions 41, 42, which interconnect the gears 29, 33 and 34. The disks 37, 38 like their components 3, 4, are counterweighted at 43, 44, and are supplied with subordinate cross counter-balance weights at 45, 46. These sets of weights are also 90° apart, but their angular spacing is so planned that there is no axial coincidence of any of the weights and the crank pins excepting at regularly recurring points in their orbital motion around the axis of the axle.

This statement has its significance in the fact that no two weights of a kind travel together at the same time in the same angular position. It has been pointed out that the counterweights 16, 17, are spaced 90° apart. This is equally true of their subordinates 18, 19. Therefore these weights describe their orbital paths on the basis of a fixed angular spacing. The same principle obtains in the spacing of the counterbalance 2. But it is readily seen that the axes of the two systems of weights must cross once in every 180° of rotation, said crossing, however, being incidental to the traveling of the weights in opposite directions.

To sum up the ultimate effect of this disposition of the weights both great and small, masses

of metal are distributed at such critical points both around the main axle 1 and around the counterbalance 2 that a perfectly harmonious rotation is secured insuring the damping out of both the vertical and horizontal vibrations (or forces which produce said vibrations) which are currently the subject of much objection.

Pins 47 driven through the axle 1 provide rests for stop collars 49 which are abutted by the disks 37, 38. Said collars provide stop means for the couples 35, 36. Thus they are kept in engagement with the pinions 41, 42.

Said pinions 41, 42, are carried by a yoke 52 which in a sense is of a floating character. This yoke and the springs (presently described) is largely responsible for compensating for loose play eventually occurring between the teeth of gears 33, 34, and pinions 41, 42. The pinions are journaled upon the shouldered stubs 53 of studs 54 that are firmly secured into the heavy bosses 55 in each of the arms 56 which give the yoke a fork shape. These arms are connected at one end by a bridge 57, the other ends of the arms being slotted at 58 (Fig. 8) to make room for the axle 1 because said arms extend slightly beyond said axle.

This arrangement provides for the touching of the axle by the inner end of the yoke, thus constituting a part of its floating support. The latter is completed by a pair of springs 59 (Fig. 7), which bear on opposite sides of a bracket 60 extending from the bridge 57. A rigid standard 61 goes through a hole 62 in the bracket and carries said springs. Nuts 63 on the threaded portions of the standard provide for tightening or loosening the tension of the springs so that the yoke may either be restricted in its yielding or made more readily adaptable to the latter in the performance of its floating function. A mount 64 of any desired description is used for the affixation of the standard 61.

A certain amount of riding of the axle 1 in the slots 24 of the bearings 20 occurs in the operation of the counterbalance. In other words, there is a tendency toward said riding of the axle in respect to the bearings as the engine driver wheels 3, 4 traverse the rails. This riding constitutes a useful absorption of movements in the axle which would otherwise evidence themselves as undesirable strains upon the bearings. It is here that the value of the yoke 52 becomes apparent because in addition to yielding to said riding movements, it keeps the pinions 41, 42, constantly in proper relationship to the contiguous gear faces, avoiding any mal-operation which would otherwise occur.

Another advantage of the yoke 52 lies in the degree of resilience which the arms 56 have. That is to say, these arms can flex a limited amount at their places of connection with the bridge 57. This makes for a mutual accommodation of the various intermeshed gears and pinions, assuring a much better working than if the yoke were rigid.

The operation is readily understood. Driving power for the axle 1 is derived from the pistons in the steam cylinders 10. Said power is delivered to the axle first through the reciprocatory motions of the piston rods 8, 9, and pitmans 6, 7. Since the latter are connected to the crank pins 14, 15, it goes almost without saying that the reciprocatory motion is converted into rotary motion according to a common and well known plan.

The counterweighting of the wheels 3, 4, which

have herein been taken to represent the engine driver wheels, is also in accordance with a known principle. In order to overcome known deficiencies in the counterbalancing functions of the weights 16, 17, and their subordinates 18, 19, use is made of the counterbalance 2 wherein the couples 35, 36, are made to rotate reversely to the direction of the axle. This is accomplished by the master or double-faced gear 29 and its intergearing with said couples as shown in Fig. 6.

Much depends upon the mounting of the pinions 41, 42. The yoke 52 not only yields to the disturbing effects upon the axle 1 transmitted thereto through the wheels 3, 4, but also responds to any inequalities in the gears themselves, yielding to such inequalities as may be necessary, all to the ultimate purpose of insuring a harmonious rotation of the counterbalance 2.

I claim:

1. The combination of the reciprocating piston rods and pitmans of an engine, an axle adapted to be rotated thereby, wheels on the extremities of the axle, each having a crank pin to which the respective pitman is connected to cause said rotation of the axle in either direction, a double faced gear situated midway of the ends of the axle and affixed to the axle to rotate in the same direction therewith, a gear and disk couple on each of the two sides of the double-faced gear, each couple including a connecting sleeve loosely mounted on the axle, pinions interconnecting the gear faces and gear couples rotating said couples counter to the axle, counterweights attached to the wheels of both the axle and couples, being angularly distributed in a uniform manner in respect to each other and to the axis of the shaft for counterbalancing the mass of the members associated with said shaft, and a yoke having means for suspending it loosely in respect to the axle, said yoke carrying the pinions and responding to inequalities in the gears because of its loose suspension.

2. The combination of the reciprocating piston rods and pitmans of an engine, an axle adapted to be rotated thereby, wheels on the extremities of the axle, each having a crank pin to which the respective pitman is connected to cause said rotation of the axle in either direction, a slotted bearing adjacent to each wheel, in which the axle is normally rested but in which it may ride up and down, a double-faced gear situated midway of the ends of the axle and affixed to the axle to rotate in the same direction therewith, a gear and disk couple on each of the two sides of the double-faced gear, each couple including a connecting sleeve loosely mounted on the axle, pinions interconnecting the gear faces and gear couples rotating said couples counter to the axle, counterweights attached to the wheels of both the axle and couples, being angularly distributed in a uniform manner in respect to each other and to the axis of the shaft for counterbalancing

the mass of the members associated with said shaft, and a yoke having means for suspending it loosely in respect to the axle, said yoke carrying the pinions and responding both to inequalities in the gears and vibration of the axle in its bearings.

3. The combination of the reciprocating piston rods and pitmans of an engine, an axle adapted to be rotated thereby, bearings for the axle, being vertically slotted to allow vertical riding of the axle and resting thereof on the bottoms of the slots, wheels on the extremities of the axle, each having a crank pin to which the respective pitman is connected to cause said rotation of the axle in either direction, a double-faced gear situated midway of the ends of the axle and affixed to the axle to rotate in the same direction therewith, a gear and disk couple on each of the two sides of the double-faced gear, each couple including a connecting sleeve loosely mounted on the axle, pinions interconnecting the gear faces and gear couples rotating said couples counter to the axle, counterweights attached to the wheels of both the axle and couples, being angularly distributed in a uniform manner in respect to each other and to the axis of the shaft for counterbalancing the mass of the members associated with said shaft, a yoke carrying the pinions and touching the axle for support at one of its ends, and a resilient support for the other end of said yoke permitting yielding in response to said riding of the axle in said bearings.

4. The combination of the reciprocating piston rods and pitmans of an engine, an axle adapted to be rotated thereby in either direction, a double-faced gear situated midway of the ends of the axle and being affixed to the axle and consequently rotated therewith, counterweight couples loose on the axle and including gears confronting the gears of the double-faced gear, a yoke having a bridge and arms extending therefrom into positions between the gears, said arms being slotted to admit the axle and provide for the support of one end of the yoke upon said axle, stubs affixed to the arms and being directed toward the slots, pinions journaled on the stubs and interconnecting the gears to produce reverse rotations of said couples, said double-faced gear, counterweight couples and pinions constituting a counterbalance unit centered upon the axial distance of the axle, a bracket attached to the bridge and having a hole, a rigid standard having occupancy of the hole, and springs mounted on the standard on each side of the bracket, bearing on opposite sides of the bracket to support the other end of the yoke and accommodate the yielding of the yoke because of inequalities in the gears and pinions, said counterweight couples including disks on the shaft and provided with balancing weights for counterbalancing the mass of the members associated with said shaft.

CARL W. CLEMENTS.
